UNITED STATES PATENT OFFICE.

CHARLES F. MILLER, OF MOORE, PENNSYLVANIA, ASSIGNOR TO WESTINGHOUSE ELECTRIC & MANUFACTURING COMPANY, A CORPORATION OF PENNSYLVANIA.

GRATE MECHANISM.

Application filed March 2, 1920. Serial No. 362,888.

To all whom it may concern:

Be it known that I, CHARLES F. MILLER, a citizen of the United States, and a resident of Moore, in the county of Delaware and State of Pennsylvania, have made a new and useful Invention in Grate Mechanism, of which the following is a specification.

My invention relates to grate mechanism and particularly to grate mechanism used in overfeed automatic stoker furnaces. One of the objects of the invention is to produce a grate surface which will support the fuel thereon without permitting it to sift through the grate into the wind box beneath.

A further object is to produce a grate which will effectively deliver ample quantities of air past the grate bars to the fuel bed so that uniform combustion is efficiently maintained throughout the entire grate surface.

A further object is to produce an inexpensive form of grate bar which may be readily assembled in the furnace or replaced.

25 A further object is to produce a grate bar which may be effectively cooled by the air passing from the wind box past the grate bars.

A further object is to produce grate bars 30 adapted to cooperate to crush any fuel or ash falling into the air delivery passages and support it in the path of the air passing the grates so that it will be returned to the fuel bed and burned.

35 These and other objects which will hereinafter appear are attained by means of the grate bar construction herein described and illustrated in the accompanying drawings wherein:

40 Fig. 1 is a fragmental perspective view of a set of grate bars embodying my invention, which bars are illustrated in transverse section.

Fig. 2 is a fragmental perspective view of 45 a modified arrangement of grate bars.

Fig. 3 is a fragmental perspective view of a grate embodying my invention, showing supports for the grate and means for reciprocating the bars.

50 Referring to the drawings, wherein a plurality of bars are shown in their assembled relation, the grate bars include two forms, A and B, the former being reciprocatory fuel supporting bars and the latter being auxiliary bars which are preferably sta-

tionary and supported on the furnace frame members 18 between the movable bars. The movable bars may be reciprocated in any well known manner, as by the rock-shaft 21, driven from any convenient source of power. 60 Each movable bar A comprises a pair of channel shaped members 3 and 4 which are joined in any suitable manner, as by the counter-sunk rivets 20, to form a hollow grate bar having a flat fuel supporting surface 5. The longitudinal edges of the bar are provided with downwardly extending flanges 5', the purpose of which will hereinafter appear. The bars A are arranged in parallel relation and are spaced apart to 70 provide an air delivery space 6 between the bars through which air is delivered to the fuel from the wind box which is usually located beneath the bars.

In the usual form of grate bar mechanisms, fuel and ashes, hereinafter referred to as siftings, fall through the air space between the grate bars and accumulate within the wind box from whence they must be removed at certain intervals through cleaning 75 and inspection openings provided in the wind box. The opening of the wind box for the purpose of cleaning the siftings therefrom disturbs the air supply to the furnace and consequently interferes with the main- 80 tenance of a uniform draft.

In order to obviate this difficulty as well as to insure the complete combustion of all the fuel delivered to the grates, the auxiliary bars B are placed so as to form channel shaped members which when placed beneath the air spaces 6 between bars A entrap all siftings falling through them. Each of the bars B includes a pair of channel shaped members 7 and 8, which are joined together to form a hollow bar having a pair of upwardly extending flanges 9 which, together with the upper wall of the bar form a channel 10 into which the downwardly extending flanges 5' project so as to form a 90 trap for retaining the siftings. The grate bars A and B are spaced apart so as to provide sinuous passages 11 between the bars through which air passes from the wind box to the air passages 6 between the bars A. It 95 will be seen that the auxiliary bars B serve to support siftings falling through the air passages, directly in the path of the air blast flowing through the air passages 11. The relative movement of the bars A and B 110

causes the siftings to be crushed between them into fine particles which are conducted by the air current along the channel 10 to a point therein where the air is passing freely 5 through the passage 6. Here they are carried upward and into the fuel bed again, where any particles of unburned fuel, such as coal or coke may be consumed. In this manner the channel 10 is constantly cleared 10 of siftings and, as a result, the passage 6 is maintained in open condition throughout its entire length, thereby ensuring a uniform distribution of air throughout the entire grate area. It will be seen that this form of 15 grate construction results in both a saving in fuel and labor.

In addition to these advantages, as shown, the bars are constructed with relatively large heat conducting side walls or webs which 20 are directly exposed to the air passing between the bars. All of the air flowing to the fuel surface moves past the side walls of the bars through the relatively narrower passages 11 formed therebetween; and, consequently, the bars are maintained at a safe 25 operating temperature and the air delivered to the furnace is heated by contacting with the bars prior to entering the fuel bed.

The bar sections forming either form of 30 bar are identical and interchangeable. The castings are simple and inexpensive to make and may be replaced with a minimum of disturbance to the remaining bars.

In Fig. 2, I have shown a modified arrangement of bars which may be used instead of the hollow bars illustrated in Fig. 1. The lower bar comprises a channel shaped portion 12 having a depending centrally disposed flange 13. The flange 35 serves both as a reinforcement to the channel member to prevent warping and as a heat conducting surface adapted to contact with the air flowing from the wind box to the fuel bed. A set of upper bars 15 having reinforcing ribs 14 and flanges 16 cooperate with the lower set of bars, the flanges 16 fitting within the channel portions 12, adjacent flanges being spaced sufficiently to provide air channels, the flanges 40 12 and 16 and the ribs 14 cooperating to constitute tortuous air passages.

While I have described and illustrated two embodiments of my invention, it will be apparent to those skilled in the art that 45 various changes, modifications, additions and omissions may be made in the apparatus described and illustrated without departing from the spirit and scope of the invention as set forth by the appended 50 claims.

What I claim is:

1. A furnace comprising a grate surface provided with upwardly opening air passages and chambers adapted to receive siftings falling through the passages and sup-

port them in the path of the air flowing to the passages whereby the siftings are forced out of the chamber through the said passages.

2. The combination with a grate for furnaces having an air passage opening upwardly into the furnace, of a member provided with a trough disposed beneath the passage for receiving siftings falling through the said passage and supporting them in the path of air flowing through the trough to the air passage so that they may be moved through the said passage to the furnace by air passing upwardly into the furnace. 70

3. The combination with a furnace grate having an air passage opening upwardly into the furnace, of a member provided with a trough disposed beneath the passage for receiving siftings falling through the said passage and supporting them in the path of air flowing through the trough to the air passage so that they may be moved through the said passage to the furnace by air passing upwardly into the furnace, and means for crushing the siftings 80 falling into the said trough. 90

4. A furnace grate comprising a plurality of bars spaced apart to form an air passage therebetween and provided at the adjacent edges with downwardly directed flanges, and a channel member beneath the air passage adapted to receive the siftings and to form with the said flanges an air passage communicating with the first air 100 passage and the air supply of the furnace. 95

5. A furnace grate comprising a plurality of bars spaced apart to form air passages therebetween, and a channel member beneath the space between the bars adapted 105 to receive the siftings and discharge air upwardly through the space between the bars, the said bars being provided with downwardly directed flanges extending into the said channel member and spaced from the bottom of the channel therein, whereby an air passage is formed between the flange and the channel member. 110

6. A furnace grate comprising a plurality of grate bars each having a hollow body portion and a top portion of greater width than the body portion provided at the edges with downwardly extending flanges, the said bars being spaced apart to form an air passage between said flange, and a plurality of hollow bars disposed between the body portions of the first bars, each provided with a depression in the upper side thereof adapted to receive the flanges of the first bars and form therebetween air passages communicating 115 with the first air passage and the air supply of the furnace. 120

7. A furnace comprising a plurality of movable grate bars each having a body portion and a fuel supporting portion provided 130

at its edges with downwardly directed flanges, the said bars being spaced apart to form an air passage between them, and a stationary member provided with a trough 5 adapted to receive the flanges of the movable bars and support the siftings falling through the grate in the path of the air flowing to the said passage.

8. A furnace comprising a plurality 10 of movable grate bars each having a body portion and a fuel supporting portion provided at its edges with downwardly directed flanges, the said bars being spaced apart to form an air passage between them, and a stationary member provided with a trough adapted to receive the flanges of the movable bars and support the siftings falling through the grate in the path of the air flowing to the said passage, the flanges of said bars and the trough of said stationary member being so constructed and disposed with relation to each other as to effect a crushing of the siftings in the trough upon movement of the bars.

In testimony whereof, I have hereunto 25 subscribed my name this twenty-sixth day of February, 1920.

CHARLES F. MILLER.
